(57) **CLAIM**

The ornamental design for a quarter package skate, as shown and described.

DESCRIPTION

FIG. 1 is a perspective view of a quarter package skate showing our new design;

FIG. 2 is a right side elevation view thereof;

FIG. 3 is a left side elevation view thereof;

FIG. 4 is front side elevation view thereof;

FIG. 5 is a top plan view thereof;

FIG. 6 is a rear side elevation view thereof; and,

FIG. 7 is a bottom plan view thereof.

The broken line showing of the portions of the skate are for illustrative purposes only and form no part of the claimed design.

The design consists of the features of ornament formed on the middle of each side of the skate. In particular, the design comprises of four raised surfaces, the first having a curved parallelogram shape being oriented downwardly, the second having a straight parallelogram shape oriented upwardly and the third and fourth each having a curved parallelogram shape and being oriented downwardly. The design further comprises of the contrasting tones which create a pattern between the mesh texture of the raised surfaces and the smooth adjacent non-raised surfaces. The figures show four variants of the designs which do not differ substantially from each other. FIGS. 1 through 7 show the first variant.
